ABSTRACT OF THE DISCLOSURE

Two-component diazotype photosensitive material containing a coupling component of the following general Formula 1 and a diazocompound of the following general Formula 2 gives a navy blue or dark blue dye-image having high density and fastness by developing in an alkaline solution or vapor.

BACKGROUND OF THE INVENTION

(A) Field of the invention

The present invention relates to two-component diazotype photosensitive material containing a compound having the following general Formula 1 as a coupling component:

(B) Description of the prior art

Two-component diazotype photosensitive material containing a diazocompound and a coupling component in a photosensitive layer has been disclosed in the Japanese patent publication No. 43/4928 (1968), said coupling component being derivatives of aminonaphthol. Such photosensitive materials have defects that they give a light purple-blue dye-image when developed in an alkaline solution or vapor and the dye-image thus obtained is easy to discolor or fade.

It is, therefore, an object of the present invention to provide two-component diazotype photosensitive material capable of giving a dye-image of high density and fastness.

2

SUMMARY OF THE INVENTION

The present invention relates to two-component diazotype photosensitive material containing a coupling component and a diazocompound in a photosensitive layer, and capable of developing in an alkaline solution or vapor and giving a vivid dye-image of high density and fastness.

The compounds having a following general Formula 1 are used as a coupling component and these coupling components are novel and have not been disclosed in the literature.

The general formula of the aforementioned coupling component is as follows:

wherein R₁ and R₂ are the same or different alkyl radical of from 1 to 4 carbon atoms, or they may be linked together with nitrogen to complete a heterocyclic ring system which may contain one or more substituents.

These coupling components are very soluble in water, do not cause to coagulate with diazocompounds to produce a clear photosensitive solution, do not contaminate the substrate of the photosensitive material and give a vivid dye-image of high density and fastness when coupled with a suitable diazocompound.

The examples of these coupling components are in following:

- 40 1-(2',4'-diimino-3'-hydro-1',3',5'-triazino)-7-hydroxy-8-dimethylaminomethyl-naphthalene (M.P. 209—211° C.),
45 1-(2',4'-diimino-3'-hydro-1',3',5'-triazino)-7-hydroxy-8-diethylaminomethyl-naphthalene (M.P. 209—212° C.),
50 1-(2',4'-diimino-3'-hydro-1',3',5'-triazino)-7-hydroxy-8-dipropylaminomethyl-naphthalene (M.P. 211—212° C.),
55 1-(2',4'-diimino-3'-hydro-1',3',5'-triazino)-7-hydroxy-8-dibutylaminomethyl-naphthalene (M.P. 211—213° C.),
1-(2',4'-diimino-3'-hydro-1',3',5'-triazino)-7-hydroxy-8-morpholinomethyl-naphthalene (M.P. 214—215° C.),
1-(2',4'-diimino-3'-hydro-1',3',5'-triazino)-7-hydroxy-8-piperazinomethyl-naphthalene (M.P. 214—215° C.),
1-(2',4'-diimino-3'-hydro-1',3',5'-triazino)-7-hydroxy-8-piperidinomethyl-naphthalene (M.P. 213—214° C.).

60 A method of producing one of the above-mentioned compounds is, for example, as follows:

1-biguaniidino-7-naphthol (sold by American Hoechst Co. under the trademark "Coupler 8") causes ring closure condensation by the reaction with formic acid to give 1-(2',4'-diimino-3'-hydro-1',3',5'-triazino)-7-hydroxy-naphthalene. This compound, 9 g. (0.033 mol), is suspended in 50 cc. of alcohol and then 10.5 g. (0.05 mol) of dimorpholinomethane are added thereto. This mixture is boiled under reflux for about 4 hours. Ash-colored crystals are separated and filtered off. The crude product thus obtained (11 g., M.P. 209—211° C.) are recrystallized from methyl alcohol to give white crystals (9 g.,

M.P. 214-215° C.) of 1-(2',4'-diimino-3'-hydro-1',3',5'-triazino)-7-hydroxy-8-morpholinomethyl-naphthalene.

The preferred diazocompounds which give a navy blue or dark blue dye-image having high density and fastness when coupled with the aforementioned coupling components, are those having the following general Formula 2:

wherein R₃ and R₄ are the same or different alkyl radicals of from 1 to 5 carbon atoms,

is a substituted or unsubstituted heterocyclic ring system and X is an anion.

Typical diazocompounds having said general formula are, for example, as follow:

- 1-morpholino-2,5-dimethoxy-4-diazobenzene chloride $\frac{1}{2}\text{ZnCl}_2$
- 1-morpholino-2,5-diethoxy-4-diazobenzene chloride $\frac{1}{2}\text{ZnCl}_2$
- 1-morpholino-2,5-diproxy-4-diazobenzene chloride $\frac{1}{2}\text{ZnCl}_2$
- 1-morpholino-2,5-dibutoxy-4-diazobenzene chloride $\frac{1}{2}\text{ZnCl}_2$
- 1-morpholino-2,5-diamoxy-4-diazobenzene chloride $\frac{1}{2}\text{ZnCl}_2$
- 1-piperazino-2,5-diamoxy-4-diazobenzene chloride $\frac{1}{2}\text{ZnCl}_2$
- 1-pyrrolidino-2,5-diethoxy-4-diazobenzene chloride $\frac{1}{2}\text{ZnCl}_2$

Sulfates of the above cited compounds may be also advantageously used.

DESCRIPTION OF THE PREFERRED EMBODIMENTS

The present invention is further illustrated by the following examples.

EXAMPLE 1

A photosensitive solution was prepared from the following ingredients:

- Water: 1,000 cc.
- Citric acid: 20 g.
- Ammonium citrate: 10 g.
- Ethylene glycol: 30 g.
- 1 - (2',4'-diimino-3'-hydro-1',3',5'-triazino)-7-hydroxy-8-morpholinomethyl-naphthalene: 28 g.
- 1 - morpholino - 2,5 - dibutoxy-4-diazobenzene chloride $\frac{1}{2}\text{ZnCl}_2$: 12 g.
- Saponin: 1 g.
- Methylene Blue: 0.05 g.

This solution was applied to a support (e.g. paper or sheet) and then dried off. The two-component diazotype photosensitive material thus obtained gave a vivid navy blue dye-image of high density, when irradiated with light in contact with an image original and subjected to development in the developing solution prepared from the following ingredients:

- Water: 1,000 cc.
- Potassium carbonate: 20 g.
- Potassium tetraborate: 30 g.
- Thiourea: 20 g.

The printed material did not show discoloration and fading.

Said photosensitive material gave also a navy blue dye-image of high density by developing in an ammonia vapor.

75

EXAMPLE 2

A photosensitive solution was prepared from the following ingredients:

- 5 Water: 1,000 cc.
- Conc. H₂SO₄: 5 cc.
- Cadmium sulfate: 10 g.
- Thiourea: 10 g.
- 10 1 - (2',4'-diimino-3'-hydro-1',3',5'-triazino) - 7 - hydroxy-8-dimethylaminomethyl-naphthalene: 20 g.
- 1-piperazino - 2,5 - diamyloxy - 4 - diazobenzene chloride $\frac{1}{2}\text{ZnCl}_2$: 10 g.
- Saponin: 1 g.
- Methylene Blue: 0.05 g.
- 15 This solution was applied to a substrate, precoated with an aqueous suspension prepared from the following ingredients, and then dried off.
- Water: 1,000 cc.
- 20 Corn starch (particle size 1-5 μ): 100 g.
- Colloidal silica (particle size 1-5 μ): 40 g.
- Vinyl acetate emulsion (solid 50%): 80 g.

The photosensitive material thus obtained gave a blue dye-image of high density by developing in an 5% aqueous solution of potassium metaborate and also gave a dye-image of good contrast by developing in an ammonia vapor.

EXAMPLE 3

- 30 The procedure of Example 1 was repeated except that 1 - morpholino - 2,5 - diethoxy - 4 - diazobenzene chloride $\frac{1}{2}\text{ZnCl}_2$ was used as a substitute for 1-morpholino-2,5-dibutoxy-4-diazobenzene chloride $\frac{1}{2}\text{ZnCl}_2$ and the same dye-image as that of Example 1 was obtained.

EXAMPLE 4

A photosensitive solution was prepared from the following ingredients:

- Water: 1,000 cc.
- 40 Oxalic acid: 5 g.
- Conc. H₂SO₄: 1 cc.
- Cadmium sulfate: 10 g.
- Thiourea: 10 g.
- 1-(2',4'-diimino-3'-hydro-1',3',5'-triazino)-7-hydroxy-8-piperidinomethyl-naphthalene: 25 g.
- 45 1-morpholino-2,5-dibutoxy-4-diazobenzene sulfate: 11 g.
- Saponin: 1 g.
- Methylene blue: 0.05 g.

The photosensitive material prepared from this solution gave a blue dye-image of higher density than that of Example 1.

EXAMPLE 5

The procedure of Example 2 was repeated except that 55 1-(2',4'-diimino-3'-hydro-1',3',5'-triazino)-7-hydroxy-8-dibutylaminomethyl-naphthalene as a substitute for 1-(2',4'-diimino-3'-hydro-1',3',5'-triazino)-7-hydroxy-8-dimethylaminomethyl-naphthalene and the same dye-image as that of Example 2.

What is claimed is:

- 60 1. A two-component diazotype photosensitive material comprising a support having a coating thereon wherein the coating contains (a) a coupling component having the following formula:

wherein R_1 and R_2 are the same or different alkyl radicals of from 1 to 4 carbon atoms and when taken together, with the nitrogen atom to which they are attached, form a 5 or 6 member saturated heterocyclic ring and (b) a diazonium compound of the formula:

wherein R_3 and R_4 are the same or different alkyl radicals of from 1 to 5 carbon atoms,

is a 5 or 6 member saturated heterocyclic ring and X is an anion, and (c) an acidic stabilizer.

2. A two-component diazotype photosensitive material as defined in claim 1 wherein said coupling component is 1-(2',4'-diimino - 3' - hydro - 1',3',5' - triazino)-7-hydroxy-8-dimethylaminomethyl-naphthalene.

3. A two-component diazotype photosensitive material as defined in claim 1 wherein said coupling component is 1-(2',4'-diimino - 3' - hydro-1',3',5'-triazino)-7-hydroxy-8-diethylaminomethyl-naphthalene.

4. A two-component diazotype photosensitive material as defined in claim 1 wherein said coupling component is 1-(2',4'-diimino - 3' - hydro - 1',3',5' - triazino)-7-hydroxy-8-dipropylaminomethyl-naphthalene.

5. A two-component diazotype photosensitive material as defined in claim 1 wherein said coupling component is

1-(2',4'-diimino-3'-hydro-1',3',5'-triazino) - 7 - hydroxy-8-dibutylaminomethyl-naphthalene.

6. A two-component diazotype photosensitive material as defined in claim 1 wherein said coupling component is 1-(2',4'-diimino-3'-hydro-1',3',5'-triazino) - 7 - hydroxy-8-morpholinomethyl-naphthalene.

7. A two-component diazotype photosensitive material as defined in claim 1 wherein said coupling component is 1-(2',4' - diimino - 3' - hydro - 1',3',5' - triazino)-7-hydroxy-8-piperazinomethyl-naphthalene.

8. A two-component diazotype photosensitive material as defined in claim 1 wherein said coupling component is 1-(2',4'-diimino-3'-hydro-1',3',5'-triazino) - 7 - hydroxy-8-piperidinomethyl-naphthalene.

UNITED STATES PATENT OFFICE
CERTIFICATE OF CORRECTION

Patent No. 3,667,955 Dated June 6, 1972

Inventor(s) Shigeaki Yoshida, et al

It is certified that error appears in the above-identified patent and that said Letters Patent are hereby corrected as shown below:

In the specification:

In column 3, line 55, change "28g" to --25g--.

In the claims:

In claim 1, lines 6-10, change the formula to read --OR₄-- in place of "OR".

Signed and sealed this 24th day of April 1973.
